UNITED STATES PATENT OFFICE.

EUGENE W. RUTHERFORD, OF NAUGATUCK, CONNECTICUT, ASSIGNOR TO GOODYEAR'S METALLIC RUBBER SHOE COMPANY, A CORPORATION OF CONNECTICUT.

VULCANIZING APPARATUS.

1,161,892.

Specification of Letters Patent. Patented Nov. 30, 1915.

Application filed February 6, 1915. Serial No. 6,419.

To all whom it may concern:

Be it known that I, EUGENE W. RUTHERFORD, a citizen of the United States, residing at Naugatuck, county of New Haven, State of Connecticut, have invented certain new and useful Improvements in Vulcanizing Apparatus, of which the following is a full, clear, and exact description.

My invention relates to vulcanizing apparatus and more particularly to a type thereof wherein the articles being vulcanized are subjected to the action of a controllable pressure.

Heretofore apparatus of the general character have been used, but the structures have not been such as to establish and maintain uniform pressure conditions throughout the apparatus.

By my present invention, I provide a structure wherein the pressure controlling apparatus will be so connected with the vulcanizing chamber as to act simultaneously and substantially uniformly at widely separated points and thus produce substantially the same pressure conditions in all parts of the chamber. This condition is desirable in that it permits the treatment of all articles in the chamber at any time under substantially the same conditions and results in greater uniformity in the quality of the goods vulcanized at the same time.

The invention has particular adaptability to that type of apparatus including a plurality of cars having a tubular frame upon which hollow forms supporting the articles are detachably mounted. The forms are in communication with said frame preferably by means of nipples and said car frames are in communication with pressure controlling apparatus for creating and maintaining a differential of pressure upon opposite sides of the articles upon the forms. By means of my invention each of the cars is placed in communication with the pressure controlling apparatus by means of a pipe system having a plurality of openings communicating with said car frames respectively, said openings being so arranged that the effective pressure or suction, as the case may be, at each of these points, will be substantially the same as at every other.

The invention consists primarily in a vulcanizing apparatus embodying therein a vulcanizing chamber, a pressure controlling apparatus, and a pipe system leading from

said pressure controlling apparatus and having a plurality of openings so arranged so that each will be at the same distance from said pressure controlling apparatus and leading into said chamber at widely 60 separated points; and in such other novel features of construction and combination of parts as are hereinafter set forth and described and more particularly pointed out in the claims hereto appended.

Referring to the drawings Figure 1 is a horizontal section of an apparatus embodying my invention, and Fig. 2 is a vertical section thereof.

Like letters refer to like parts in both of 70 said views.

In the accompanying drawings I have shown an embodiment of the invention wherein a plurality of cars having tubular frames are used, and the vulcanizing medium is introduced to the chamber about the articles on said cars. The vulcanizing chamber 1, is of the usual, or any desired, construction, and the walls thereof may be jacketed or otherwise equipped to minimize 75 heat radiation or assist in raising the temperature within the chamber to, or maintaining it at, the vulcanizing point. This chamber is provided with the usual tracks 2 and closure 3. In connection with said chamber 1, I provide any desired form of pressure controlling apparatus shown conventionally at 4, as a suction pump. Communicating with the said apparatus 4 is a pipe system including the main pipe line 5. The wall 80 of the chamber 1 has an opening therethrough at 6 and said pipe line 5 passes through said opening and into said chamber, suitable packing being provided about said pipe and said opening 6.

When the apparatus shown is in use, a plurality of cars 7 are run upon the tracks 2 into the chamber 1. Each of these cars has a tubular frame 8, the bars of which are provided with a plurality of hollow nipples 9 communicating with the interior of said frame. Mounted upon and communicating with each of said nipples is a hollow form 10 supporting the article to be vulcanized. These forms 10 are provided with fluid ducts 100 as 10' to permit the withdrawal of fluids in the article through said form.

The pipe system is provided with a plurality of openings communicating with the main pipe line 5 and corresponding in num- 110

ber with the cars used in the vulcanizing chamber. All of these openings are at the same conduit distance from the apparatus so that with a constant rate of flow of the fluid withdrawn from or delivered to the vulcanizing chamber, such as will result from the employment of a single pipe connection having extensions or branches provided with openings, all at the same conduit distance from the pressure-controlling apparatus, the effective suction or pressure will be equal at all of said openings. Hence by arranging these openings at widely separated points in the vulcanizing chamber, an equal suction or pressure will be simultaneously set up at all of the openings and fluids will be withdrawn from or delivered to different parts of the vulcanizing chamber in substantially the same amounts. This insures substantial uniformity in the pressure conditions throughout all parts of the said chamber. This system of piping is particularly adapted for use in connection with cars, as herein shown and described.

In the drawings pipe extensions or branches are shown at 11 and 12, each of said extensions or branches being provided with end fittings 13 and 14, 15 and 16 at opposite ends thereof respectively. Communicating with each of the branch pipes 11 and 12 at a point equidistant from each end fitting, is a pipe section 17 having a T-fitting 18 centrally of the length thereof. The main pipe line 5 is connected with said T-fitting. The end fittings may be provided with the usual form of couplings as shown, thereby providing ready means for connecting and disconnecting the cars and the piping system.

From the foregoing description it will be observed that the conduit distance between each end fitting and the pressure-controlling or suction apparatus is the same and that therefore the effective suction or pressure at each opening and the rate of flow of the fluid entering and passing through each branch pipe will be the same, and substantially uniform pressure conditions within each car 7 will be maintained.

While I have shown four end fittings, it is apparent that the number may be varied according to the dimensions of the vulcanizing chamber. Furthermore, any opening may be closed without modifying the operative effect as to the remaining intake fittings.

It is essential that the length of the piping between each end fitting and the main pipe line, or the pressure-reducing or suction apparatus shall be the same, and any arrangement by which this condition may be established will accomplish the purpose of my invention.

While I have described my apparatus in connection with the creation of a vacuum or

partial vacuum within the vulcanizing chamber or the cars therein, it is apparent that the apparatus may also be used in raising the pressure, or for alternately raising and lowering it, if desired.

Having described my invention, what I claim as new and desire to have protected by Letters Patent is:

1. A vulcanizing apparatus embodying therein a vulcanizing chamber, a pressure controlling apparatus and a pipe system leading from said pressure controlling apparatus and having a plurality of openings so arranged as to be at the same conduit distance from said pressure controlling apparatus, and leading into said chamber.

2. A vulcanizing apparatus embodying therein a vulcanizing chamber, a pressure controlling apparatus and a pipe system leading from said pressure controlling apparatus and having a plurality of end fittings so arranged as to be at the same conduit distance from said pressure controlling apparatus and located in said chamber, and a coupling carried by each of said fittings whereby it may be connected with an article support.

3. A vulcanizing apparatus embodying therein a pressure controlling apparatus and a pipe system including therein a main pipe line communicating with said pressure-controlling apparatus and a plurality of extensions or branches communicating with said main pipe line, each of said extensions or branches having an opening and all of said openings being of equal conduit distance from said main pipe line.

4. A vulcanizing apparatus embodying therein a pressure controlling apparatus, and a pipe system including therein a main pipe line communicating with said pressure-controlling apparatus, a pipe section, a connection centrally of the length of said pipe section, whereby said section is placed in communication with said main pipe line, two extensions or branches having openings adjacent the ends thereof respectively and a connection between said extensions or branches respectively, and opposite ends of said pipe section arranged substantially equi-distant from both of the openings of its extension or branch, whereby all of said openings are at the same conduit distance from said main pipe line.

5. A vulcanizing apparatus embodying therein a pressure controlling apparatus and a pipe system including therein a main pipe line communicating with said pressure controlling apparatus, a pipe section, a connection centrally of the length of said pipe section, whereby said section is placed in communication with said main pipe line, two extensions or branches, and fittings therefor respectively, a coupling carried by each of said fittings whereby it may be connected

with an article support, and a connection between said sections or branches respectively and opposite ends of said pipe sections, arranged substantially equi-distant from both of the end fittings of its extension or branch, whereby all of said openings are at the same conduit distance from said main pipe line.

Copies of this patent may be obtained for five cents each, by addressing the "Commissioner of Patents, Washington, D. C."

Signed at Naugatuck, county of New Haven, State of Connecticut, this 3rd day 19 of February 1915.

EUGENE W. RUTHERFORD.
